INVENTOR.

John Sisolak
BY Arnold Dubois

ATTORNEY.

UNITED STATES PATENT OFFICE.

JOHN SISOLAK, OF CHICAGO, ILLINOIS.

WRENCH.

Application filed November 17, 1924. Serial No. 750,310.

To all whom it may concern:

Be it known that I, JOHN SISOLAK, a citizen of the Republic of Austria, residing at Chicago, in the county of Cook and State 5 of Illinois, have invented certain new and useful Improvements in Wrenches, of which the following is a specification.

This invention relates to new and useful improvements in wrenches and more particularly to a universal wrench.

The main object of my invention is the provision of a wrench carrying movable heads having a plurality of various size sockets therein whereby the wrench may be 15 quickly adapted for use on nuts or bolt heads of various sizes.

Another object of my invention is the provision of a wrench having movable heads provided with various size sockets or 20 receiving openings whereby the heads may be readily positioned for operating upon nuts or bolt heads of various sizes and wherein the wrench may be disposed at different angles and, at the same time, readily 25 grasp the nut or bolt head to be operated upon.

A further object of my invention is the provision of a wrench including a shank or handle portion having sockets at each end 30 thereof mounted for rotative movement with respect to the handle and provided with various sized sockets for operating upon different sized nuts and whereby the various 35 sockets through the rotation of the heads may be quickly and readily brought into position for use.

With the above and other objects in view, the invention consists in the novel features of construction, the combination and arrangement of parts hereinafter more fully 40 set forth, pointed out in the claim and shown in the accompanying drawings, in which:

Figure 1 is a top plan view of a wrench 45 constructed in accordance with my invention,

Fig. 2 is a side elevation,

Fig. 3 is an end elevation, and

Fig. 4 is a transverse section on the line 50 4-4 of Fig. 1.

Referring more particularly to the drawings, the numeral 1 indicates the handle or body portion of the wrench, the ends of which are enlarged as at 2, and projecting 55 from the enlarged portions 2 are the spaced

ears 3 which are bifurcated to receive the pins 4 which form an axis for the rotatable head members 5 movable between the ears 3. The head members, as illustrated in the drawings, are preferably rectangular in shape, having each face thereof flattened as shown at 6, and the faces of the heads, which are at right angles to the axes thereof, are provided with sockets 7, each face being provided with a different size socket or opening 60 7 all of the sockets being disposed in the same position relative to the faces, whereby the device may be readily used for operating upon nuts and bolt heads of various sizes and whereby the wrench may be used to operate on nuts which are spaced from the 65 ends of rods, bolts or the like.

The pins 4, which form the axes for the rotatable heads 5, extend through the ears 3 and through opposed side walls of the 70 heads, as illustrated in Figure 4, the inner ends of the pins being situated in the walls of the head so as not to produce any projections upon the interior of the head. It 75 will be apparent from the illustration in Figure 4 that the heads 5 are hollow in cross-section so that they may not only be applied to nuts or bolt heads of various sizes, but may be engaged with rods of various sizes, providing the rod is of a size 80 to fit and conform to the shape of the lowermost opening, when the wrench head is in a position as shown in Figure 4. It will also be noted that the handle member 1 may be 85 disposed at various angles to the work in accordance with the particular socket of the 90 head being used, the handle, after the head has been engaged with the work, pivoting upon the pins 4.

It will be apparent from the foregoing, 95 that I have provided a simple and inexpensive wrench particularly adapted for use in operating upon nuts and bolts wherein a single wrench may be used for engaging various sizes of nuts and bolt heads, and the 100 handle member thereof may be disposed at various angles with respect to the engaging head. It will be apparent that by the use of a wrench of this character it will be possible to engage nuts and the like where it 105 is rather unhandy to use an ordinary type of wrench.

While I have shown and described the preferred form of my invention, it will be understood that various changes and altera- 110

tions may be made without departing from the spirit of the invention or the scope of the appended claim.

Having thus described my invention, what I claim is:

- A wrench, including a handle, having its ends extending laterally into enlargements, spaced ears projecting from said enlargements and having aligned openings there-through, substantially rectangular socket heads between said ears, bearing pins ex-tended through the openings in the ears and projecting transversely through the side
- 10

walls of said socket heads and having their inner ends upset and embedded in the walls 15 of the socket heads, said pins being mounted for rotation in the openings in the ears, and said socket heads having each face thereof at right angles to the ears provided with an opening, the openings in the faces of said 20 socket heads being of different sizes and all disposed in the same position relative to the faces.

In testimony whereof I affix my signature.

JOHN SISOLAK.
